(57) **CLAIM**

The ornamental design of a vehicle lower door sill, as shown and described.

DESCRIPTION

FIG. 1 is a front right top perspective view of a vehicle lower door sill according to the present invention.

FIG. 2 is a front right perspective view of the lower door sill shown in FIG. 1.

FIG. 3 is a rear left top perspective view thereof.

FIG. 4 is a rear left perspective view thereof.

FIG. 5 is a front view thereof.

FIG. 6 is a rear view thereof.

FIG. 7 is an enlarged left side view thereof.

FIG. 8 is an enlarged right side view thereof.

FIG. 9 is a top view thereof.

FIG. 10 is a bottom view thereof; and,

FIG. 11 is an environmental front view of the vehicle lower door sill in FIGS. 1–10, mounted on a vehicle.

The broken lines form no part of the claimed design but are instead included to show environmental structure.

1 Claim, 9 Drawing Sheets
